FUSE FOR PROJECTILES AND PARTICULARLY FOR SMALL CALIBER HIGH EXPLOSIVE PROJECTILES

Valentin Schläfer, Sommerda, Germany, assignor to Rheinische Metallwaren- und Maschinenfabrik, Dusseldorf-Derendorf, Germany, a corporation of Germany

Application December 26, 1933, Serial No. 704,022
In Germany July 13, 1932

3 Claims. (Cl. 102—37)

The invention relates to projectile fuses, intended particularly for anti-aircraft guns, the explosive charge of which, owing to the high sensitivity of their percussion fuse devices, explodes 5 and effects the bursting of the projectile when it strikes an aerial target, and which, if the target is missed, acts in such a manner that the projectile does not reach the ground as a compact explosive body, but bursts in the air and is split 10 up into small fragments. These fuses are, in their general construction, time and percussion fuses, that is in addition to percussion fuse devices there are provided devices which after a certain, constant, fixed time of flight, set the time 15 ignition in operation. The moment when the projectile automatically bursts after having missed the target is preferably in the falling part of the trajectory.

The object of the invention is to produce a fuse 20 which possesses the above-mentioned properties with the maximum reliability of action and sensitivity when striking the target, is very safe during transport and when in the barrel and also over a greater initial portion of the trajectory 25 of predetermined length. It is intended that the construction of the fuse shall be simple, slight in bulk, and be particularly suitable for small caliber high explosive projectiles of the order of magnitude of 2 cm. to about 4 cm. diameter or even 30 more.

The combined time and percussion fuse according 35 to the invention possesses in common with both kinds of fuse, namely the percussion fuse and the time fuse, a percussion fuse device consisting of a movable detonating pin with an oppositely disposed primer which acts as the initial detonator for the explosive charge of the projectile. For the sake of safety during transport, when the projectile is in the barrel and over a 40 path of flight up to about 100 m. from the mouth of the barrel, the detonating pin is locked by a safety member which is effective for a predetermined length of time even after the projectile has been fired. The percussion fuse is set in operation 45 by a plunger bearing against the detonating pin and actuated by the impact when a target is struck, and in parallel thereto (if the projectile misses the target and in order that the time fuse may be brought into operation) the detonating pin is moved on to the primer by a second actuating means released after a "constant fuse running time". According to the invention the 50 simple construction of the fuse is attained in that a detonating pin plunger acting on a percussion detonating device common to both kinds of deto-

nation (percussion and time), consists entirely or partly of a column of powder, which, when percussion ignition does not occur after a constant time interval of the fuse has elapsed, is caused to detonate and acts as a striking charge, exerting 5 a driving force on the detonating pin.

A typical fuse according to the invention is illustrated in the accompanying drawing, in which:

Figure 1 is a longitudinal sectional view of 10 the fuse.

Fig. 2 is a similar view taken at another angle to that of Fig. 1.

Fig. 3 is a cross-sectional view of the fuse taken 15 on line C—D of Fig. 1, and

Fig. 4 is a cross-sectional view of the fuse taken on line A—B of Fig. 1.

In the fuse shown, the plunger *b* is adapted to be displaced longitudinally in a central longitudinal bore in the body *a* of the fuse between a forwardly disposed closing member *c* and the detonating pin *d*. The movable detonating pin is located opposite the primer *e*, which in known manner consists of a detonator with a percussion detonating material placed immediately in front of 20 the explosive material. A "loose" member *f* secures the detonating pin *d* against movement to detonate and is, in its turn, secured in position to effect this by a powder charge *g*. To this charge 25 opens a channel *h* (Fig. 3), the other end of the channel being open to a longitudinal bore *k* in the body of the fuse in which is a second detonating pin *i* (Figs. 2 and 3). When the projectile is 30 fired a primer *l* by reason of its inertia is shot towards this detonating pin *i* against the influence of the retaining springs *l'* which tend to 35 press it forward and is thereupon ignited. The flame due to this ignition then passes on the one hand through the channel *h* to the powder charge of the detonating needle safety device *f*, and on the other hand through a second channel *m* to the rear end of a powder train *n*, the front part of which ends at the cross duct *o* which terminates 40 near the middle portion of the plunger *b*.

At the position where the cross duct *o* ends, and consequently also the end flash of the powder train *n* comes into contact with the plunger *b*, the cross-section of the plunger—which is made, for instance of wood—is reduced to a thin stem which 50 joins the end portions of the plunger, and the space so formed is filled by a mass of powder *p* so that the cylindrical form of the plunger is retained. This column of powder *p* is ignited by the end flash of the powder train *n* and in exploding 55

acts as a percussion charge exerting a driving force on the rear part of the plunger and, therefore, on the detonating pin *d* so that the primer *e* is ignited. The plunger *b* may instead consist of 5 separate, loosely assembled components with a column *p* of powder constituting the middle member, or it may consist of a column of powder alone.

On the gun being fired, when the projectile is set in motion the detonating pin *i* detonates the primer *l* which in consequence of its inertia is shot back on to it and the consequent flame ignites, on the one hand, the powder train *n*, and on the other hand the "locking" powder charge *g* of 10 the detonating pin safety device *f*. This is so formed, as regards its composition and size, that after an interval of time sufficient to ensure the safety of the fuse while in the barrel and also 15 during the initial part of the trajectory, for instance for a time of 0.1 second, and for a distance of about 100 metres from the nozzle of the gun, the "loose" member *f* is caused by centrifugal force to move into a position which allows the release of the detonating pin *d*. Then, and not until then, is 20 the fuse "live"; when the projectile strikes a target, the detonating pin *d* is driven by the plunger *b* into the primer *e* so that instantaneous detonation is produced. If the projectile does not hit a target, the powder train *n* which likewise is 25 completely ignited after a predetermined time has elapsed (for instance 8 seconds), causes the powder column *p* of the plunger *b* to ignite and explode. The gases thereby generated force the 30 part of the plunger bearing against the detonating pin *d*, and therefore the detonating pin itself, against the primer *e*, and its detonation 35

causes the explosion of the explosive charge and the disintegration of the projectile.

I claim:—

1. In a time and percussion fuse for projectiles, a detonating pin consisting at least partially of explosive material, a percussion member co-operating with said pin, means preventing actuation of the detonating pin by the percussion member, means for releasing the detonating pin from the preventing means at a predetermined interval after firing the projectile, and means for igniting the explosive material of the detonating pin at an interval after firing the projectile greater than said first mentioned interval. 10

2. In a time and percussion fuse for projectiles, 15 a detonating pin consisting at least partially of explosive material, a percussion member, means for placing the detonating pin under the control of the percussion member only after a certain interval from the instant of firing, and means for 20 igniting the explosive material of the detonating pin after a longer interval from the instant of firing.

3. In a time and percussion fuse for projectiles, 25 a detonating pin consisting at least partially of explosive material, a percussion member contacting said pin, a locking member engaging said pin to prevent its operation by the percussion member, means operative after a certain interval from the firing of the projectile to cause 30 the locking member under the action of centrifugal force to disengage the detonating pin, and means for igniting the explosive material in the detonating pin after a longer interval from the instant of firing. 35

VALENTIN SCHLÄFER.
